FIG. 5.

UNITED STATES PATENT OFFICE.

WALTER WRIGHT, OF NEW YORK, N. Y., ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,259,701.

Specification of Letters Patent.

Patented Mar. 19, 1918.

Application filed January 4, 1912. Serial No. 669,845.

To all whom it may concern:

Be it known that I, WALTER WRIGHT, a citizen of the United States, residing in New York city, in the county of New York and State of New York, have invented certain new and useful Improvements in Combined Type-Writing and Computing Machines, of which the following is a specification.

- 10 This invention relates to a new and improved key controlled correction mechanism which may be used in connection with a combined typewriting and computing machine of the Underwood-Wright type, and is an improvement on the application of Wright and Degener, No. 543,603, filed February 12, 1910, (now Patent No. 1,237,008, dated August 14, 1917,) and my applications No. 660,392, filed November 15, 1911, and No. 663,216, filed December 1, 1911, (now Patents Nos. 1,245,300 and 1,245,301, dated November 6, 1917).

In my above-mentioned application No. 663,216, I have shown how the state of a plurality of computing heads, as to the character of computation carried on thereby, can be changed simultaneously to temporarily reverse their individual operations without interfering with their individual controlling mechanisms, by reversing the direction of drive thereto from the motor. Means was also disclosed whereby the back spacing key could concomitantly shift the carriage back a space and effect the above-mentioned reversal and change of state. It is often desirable to obtain such a change of state and reversal without a concomitant movement of the carriage, and also from a point most convenient to the operator.

40 A feature therefore of this invention is the provision of keys whose purpose is to effect a temporary and semi-permanent change of state of one or more computing heads by a reversal of the direction of drive from the motor thereto.

A further feature of this invention is the provision of silencing keys which act to render one or more heads inoperative by interrupting the drive from the motor thereto.

50 These features may be accomplished by providing for each of the computing heads

individual controlling mechanism, which shifts concomitantly clutches controlling the drive and direction of drive of both the master wheel and the tens-carrying mechanism. The gearing for driving these clutches may be connected to the source of power by a train of gearing which includes a clutch for the gearing driving the master wheels and a clutch for the gearing driving the tens-carrying mechanism, which is shiftable to any one of three positions corresponding to rotations of the master wheel and tens carrying mechanisms in two directions, and the non-rotation of the master wheels and the tens carrying mechanisms and the gearing for driving the same. These latter clutches are controlled by a main controlling mechanism which is adapted to shift them simultaneously.

This main controlling mechanism may be operated from any one of four keys, two of which are for temporary adjustment and two for permanent adjustment. Two of each of these pairs of keys shift the clutches on the common or main drive from a normal position, in which they are held by a spring and which corresponds to a rotation of the gearing for driving the master wheels and tens carrying mechanism in one direction, to such a position that these gearings will drive the master wheels and tens carrying mechanism of the computing heads which happen to be active in just the opposite direction. These keys may therefore be called reversing keys. The other two of the pairs of keys will shift the clutches on the main or common drive to an intermediate point corresponding to the disconnection of the master wheel and tens carrying gearings from the main drive, and thus corresponding to a silencing of all of the computing heads. Hence these latter keys may be called silencing keys.

One of the reversing keys and one of the silencing keys, after having once been depressed, are locked in their depressed position by latches, so that the reversal or silencing can be in effect until these latches are released. These latches, which embody the locking means for the semi-permanent silencing and reversing keys, can be re-

leased by a depression of one of the temporary keys, for which purpose connections are provided between these latter keys and the locking means.

5 Other features and advantages will hereinafter appear.

In the accompanying drawings,

Figure 1 is a side view in elevation with parts in section.

10 Fig. 2 is a diagrammatic perspective view, showing the connection between one of the numeral keys and the valuating or escapement mechanism, whereby the extent of rotation of the master wheel is controlled 15 according to the value of the particular numeral key struck.

Fig. 3 is a vertical section through one of the computing heads.

20 Fig. 4 is a skeleton perspective view, showing the connection between the several temporary and permanent reversing and silencing keys and the controlling mechanism for the main or common drive between the motor and the gearing more nearly connected 25 to the computing head.

Fig. 5 is a fragmentary view in side elevation, showing the reversing mechanism for the main drive in its normal position.

Fig. 6 is a vertical detail section, showing 30 the means for shifting one of the clutches.

Fig. 7 is a detail of the tens-carrying driving gearing.

35 Fig. 8 is a detail, showing one of the permanent shifting keys, in this instance the reversing key, in its actuated and locked position.

40 Referring more particularly to the separate parts of this invention as embodied in the form shown in the drawings, 1 indicates letter keys and 2 numeral keys, which are secured to key levers 3, which operate through the intermediary of bell cranks 4, type bars 5, so as to swing the latter up against the front side of a platen 6 carried 45 by a carriage 7, which runs on one or more rails 8. The letter-feeding movement of the carriage 7 may be obtained in the usual manner step-by-step at each actuation of a key by the release of an escapement mechanism, indicated generally by the numeral 50 9, which may be of the usual Underwood type.

55 The computing mechanism may be controlled from the numeral keys 2 in the manner described in application No. 543,603, wherein it was shown that each numeral key lever 3 was adapted to pull down on a link 10, so as to rock a bell crank 11, thereby pulling on a link 12 to swing a lever 13 60 about its pivot 14. The swinging of each of the levers 13, of which there is one for each numeral key, plunges a jack 15 against a corresponding pin 16 provided in a valuating wheel 17. The valuating wheel 17 is 65 normally held from rotation by one of the

projected pins 16 engaging an escapement wheel 18, which is secured to another escapement wheel 19 engaging one of a pair of locking stops 20 on a rock shaft 21.

The rock shaft 21 is oscillated at each 70 actuation of a numeral key, so as to release the escapement wheels 18 and 19, and thus permit a rotation of the valuating wheel 17 a predetermined amount, depending upon the particular numeral key actuated, until 75 the next projected pin 16 engages the escapement wheel 18. The rocking of the shaft 21 may be accomplished by a collar 150 being pushed back by each of the levers 13 at the actuation of a numeral key against 80 the tension of a spring 151, so as to oscillate a lever 152 which is connected by a link 153 to an arm 154 on the shaft 21.

This mechanism, which may be termed the "escapement or valuating mechanism" 85 for the computing mechanism, determines the extent of rotation of a shaft 22, to which the valuating wheel 17 is secured, and which is provided with a gear 23 meshing with a corresponding gear 23' on a shaft 24. The 90 shaft 24 is also provided with a bevel gear 25 meshing with bevel gears 26 and 27 secured respectively to shafts 28 and 29. The shaft 29 is driven from a motor 30 through the intermediary of a slip clutch not shown, 95 and also through the intermediary of intermeshing bevel gears 31 and 32, the latter of which is secured to the shaft 29. The shafts 28 and 29 form a portion of the gearing 100 connecting the motor 30 with the gearing for driving the rotatable parts of one or more computing heads 33 and 34, of which two are shown.

Each of the computing heads is preferably of the type shown in application No. 105 543,603 above-mentioned, and includes, as will be seen by reference to Fig. 3, a master wheel 35 splined on a shaft 36, so as to have a movement relative to a series of computing wheels 37, whereby it will be capable 110 of engaging with the internal gears 38 provided by the inwardly projecting teeth of these computing wheels, thus enabling the master wheel to successively actuate each of these computing wheels. The relative movement of the master wheel and the computing wheels may be obtained in any suitable manner, as for example that described in my co-pending application No. 574,813, filed August 1, 1910, (now Patent No. 120 1,244,398, dated October 23, 1917), whereby the master wheels are manipulated step-by-step at each new column by a lever 105 provided with an automatic catch 100, which is engaged and operated by a series of 125 column stops 101 carried by a rack 102 on the carriage 7. These computing wheels are also provided with external teeth forming external gears 39 meshing with the gears 40 carrying the dial wheels 41, so that the 130

numerals marked on the dial wheels will be exhibited through an opening 42 in the casing of each computing head, thereby showing the particular computation run up 5 by the numeral keys.

- Each of the shafts 36 for the computing heads 33 and 34 is provided with a bevel gear, indicated for the respective computing heads by the numerals 43 and 44. 10 These bevel gears each mesh with a pair of bevel gears loosely mounted on a shaft 45 and faced in opposite directions, so as to be capable of rotating the gears 43 and 44 in opposite directions, according to which 15 member of the pair is rotated. To connect the pairs of bevel gears, which are indicated by the numerals 46, 47, 48 and 49, in driving relation with the shaft 45, there are provided clutches 50 and 51 splined on the shaft 20 45, so as to be shiftable to cause the teeth provided on opposite ends thereof to engage with corresponding teeth on the inwardly facing sides of each member of the pairs of bevel gears. 25 Each of the clutches is provided with a circular groove, so as to be engaged by pins 52 carried by shifting levers 53 and 54. The shifting levers 53 and 54 are pivoted respectively at 55 and 56 by means of pins, and 30 are capable of occupying any one of three positions corresponding to the connection of each of the gears of a pair in driving relation with the shaft 45, and also with a neutral position in which neither gear of the 35 pair is in driving relation with the shaft 45. To secure the levers 53 and 54 in any position of adjustment, they are provided with a plurality of notches 57, preferably three in number, which are engaged by spring 40 detents 58.

To connect the shaft 45 with the shaft 28 so that there will be an unbroken drive between the motor 30 and the master wheels 35, the shaft 45 has secured thereto a bevel 45 gear 59, which meshes with a pair of oppositely facing bevel gears 60 and 61 loosely mounted on the shaft 28, but capable of being connected in driving relation therewith by a clutch 62, which is splined on the shaft 50 28, and has teeth on opposite ends thereof capable of engaging with corresponding teeth on the inwardly facing sides of the gears 60 and 61.

In the type of computing head shown 55 herewith, it is essential to transfer a complete rotation of one of the lower computing wheels 37 to a partial rotation of the next highest computing wheel in the series. For this purpose, there is provided a tens carrying 60 mechanism indicated in general by the numeral 63, which depends for its action, as described in application No. 543,603, on the rotation and direction of rotation of a rubber roller 64. This rubber roller 64, in the 65 case of computing heads 33 and 34, respec-

tively, is connected to bevel gears 66 and 67 by a train of gearing, described in application No. 543,603, and indicated in general by the numeral 65. The bevel gears 66 and 67 mesh with pairs of bevel gears loosely mounted on a shaft 68, and indicated by the numerals 69, 70, 71 and 72. The pairs of bevel gears may be connected in driving relation with the shaft 68, so as to drive the bevel gears 66 and 67 in different directions 70 by means of clutches 73 and 74, which are splined on the shaft 68, and capable of being slid, so that the teeth on opposite ends thereof will engage with corresponding teeth on the inwardly facing sides of each member 75 of the pair of gears. The clutches 73 and 74 are provided with circular grooves engaged by pins 75 mounted on supplementary levers 76 and 77, which are pivoted respectively on pins 78 and 79 secured respectively 80 to the main shifting levers 53 and 54. These supplementary levers are each provided with a pair of fingers 80 and 81 projecting on opposite sides of the pivot pins 55 and 56, so as to permit a limited motion of the supplementary levers relative to the main shifting levers. This limited motion or play may be taken up by springs 82 and 83, which are secured at one end to the supplementary 85 levers and at the other end to the pins 78 and 79. It will thus be seen that, by a simple movement of one of the levers 53 and 54, both of the clutches controlling the rotation and direction of rotation of both the master wheel and the tens carrying mechanism of 90 a computing head can be simultaneously shifted, and thereby form a controlling mechanism for the state of the computing head, as to adding, subtracting or remaining neutral or inactive. 95

The shaft 68 may be also driven from the motor 30 by being provided with a bevel gear 84, which meshes with a bevel gear 85 secured on a counter shaft 86, which has a bevel gear 87 meshing with a bevel gear 88 100 on a shaft 89. The shaft 89 may be driven from the shaft 29, which as has been stated before is driven from the motor 30, by being provided with a gear 90 fixed thereon and meshing with both members of a pair of 105 gears 91 and 92 loosely mounted on the shaft 29, and facing in opposite directions, so as to be capable of driving the shaft 89 in opposite directions. 110

To connect the gears 91 and 92 in driving 115 relation with the shaft 29, there is located between them a clutch 93 splined on the shaft 29 and shiftable from a position with its teeth on one end in engagement with corresponding teeth on the inner side of the gear 91 to a position with the teeth on the opposite end thereof in engagement with corresponding teeth on the inner face of the gear 92. 120

It is desirable that both the clutch 62 and 125

the clutch 93 be shifted simultaneously, so as to concomitantly control the direction of drive of the gearing for the master wheels and the gearing for the tens carrying mechanisms of all of the computing heads. For this purpose, a shifter 94 is provided, which is shown in the form of a rod slidably mounted in bearings 95, and having a pair of arms 96 and 97, which engage in circular 10 grooves in the clutches 62 and 93.

The shifter 94 is normally held in the position illustrated in Fig. 1 by a spring 106. To manipulate the shifter 94 to a neutral or a reversed position, there is provided a pin 107 on the rod of the shifter, which engages a slot 108 in an arm 109 secured to a shaft 110. The shaft 110 may be actuated from a shaft 111 through the intermediary of intermeshing fragmentary 15 bevel gears 112, 113, fixed respectively on the shafts 110 and 111. To rock the shaft 111, and thus manipulate the shifter 94, there are provided a plurality of keys 114, 115, 116 and 117. The keys 114 and 115 operate 20 the shaft 111 by means of a crank 118 thereon, and the keys 116 and 117 operate said shaft 111 by a crank 119 thereon.

Each of the keys 114 to 117 is pivoted intermediate its ends, as at 120, and comprises the usual finger rests 121 and levers 122. All of these keys are provided adjacent their rear end with cam edges 123, engaging pins 124 and 125 located respectively on the cranks 118 and 119. These cam edges, 35 on an actuation of any one of the keys, are adapted to rock the cranks 118 and 119, and thus the shaft 111, until the pin 124 or 125 enters into the particular slot 126 or 127 of the key operated. It will be noted that 40 the slots 126 and 127 will lock the shaft 111 against further rotation after they have once engaged with the pins 124 and 125. It will be further noted that the inclined cam edges 123 leading to the slots 126 and 127 are 45 longer in the case of the slots 127 than in the case of the slots 126, so that the shaft 111 will be rotated an appreciably greater distance, before it is stopped, by entering the slot 127. The reason for this is that the 50 shifter 94 is manipulated different distances according to whether it is desired to merely bring the clutches 62 and 93 out of engagement with the clutch faces with which they are normally held by the spring 55 106, or whether it is desired to entirely shift the clutches 62 and 93 to their opposite limit of travel in engagement with the gears 60 and 91.

The keys 115 and 116, which are provided with the slots 126, merely shift the clutches 62 and 93 to an intermediate or neutral position which corresponds with the disconnection or interruption of the drive from the motor to the actuating mechanism 65 of the computing heads embodied in the

master wheels and tens carrying mechanisms. These keys are therefore called the silencing keys.

The other keys 114 and 117, which are provided with the slots 127, will manipulate the shifter 94 to the extreme limit of its throw, so as to reverse the drive from the motor to the computing heads. These keys are hence called reversing keys.

The keys 114 and 115, after once being 75 depressed, are automatically returned to their normal positions by springs 128. These keys are hence called temporary reversing and silencing keys, because their action is merely in effect while the operator 80 holds them in their depressed position.

The keys 116 and 117, however, when once depressed, are secured in their depressed positions by locking mechanism, which is shown in this instance to comprise 85 pins 129 located on the sides of the key levers which are engaged by latches 130 secured to a rod 131. These latches 130 are normally held in position to engage the pins 129 by a spring 132.

If it is desired to disengage the locking mechanism so as to release whichever one of the permanent or semi-permanent keys 116 and 117 which happen to have been depressed, it is merely necessary to depress 95 the corresponding one of the temporary keys 114 and 115, when pins 133 secured to the side of the levers for the keys 114 and 115 will engage cam edges 134 of arms 135 secured to the rock shaft or rod 131. The 100 movement of one of these keys 114 and 115 will thus swing the latches 130 from engagement with the pins 129 on the key which happens to be depressed, so that this key 105 may be returned by its spring 136, one of which is provided for each of the permanent keys 116 and 117.

In the operation of the device, if it is found necessary to reverse the action of the machine without interfering with the individual controlling mechanism for the computing heads, that is, without shifting the levers 53 and 54, of such of the computing heads as may be active, the key 114 can be depressed, if the desired reversal is but of 115 a temporary character, as for the correction of a single numeral. The depression of the key 114 will rock the shaft 111, thereby manipulating the shifter 94 from the position shown in Fig. 1 to the position shown 120 in Fig. 5, so that the shafts 45 and 68 will be driven in the opposite direction. If any of the numeral keys should happen to be struck while this key is depressed, such of the computing heads as happen to have their 125 levers 53 and 54 in their active position will be rotated in an opposite direction to a normal one corresponding to the particular position of their controlling levers.

When the pressure on the key 114 is re- 130

leased, the spring 128 will return it to its normal position, and the spring 106 will return the shifter 94 and the actuating mechanism more directly connected thereto to its normal position, so that the clutches 62 and 93 will be shifted from the position shown in Fig. 5 to the position shown in Fig. 1.

If it is desired to temporarily disconnect all of the computing heads, as for example when it is desired to insert matter carrying a numeral which it is not desired to compute, such as the date, then the key 115 can be depressed and held in its depressed position while this numeral is struck. This key 115 will cause a shifting of the clutches 62 and 93 and the tension of the spring 106 to an intermediate position out of engagement with all of the clutch faces on the gears 60, 61 and 91 and 92.

If a permanent or semi-permanent reversal or silencing of the computing heads is desired, as for example when the operator has considerable correction or matter to be put in which necessitates either the reversal or silencing of the computing mechanism and at the same time necessitates the use of both the operator's hands, then one of the keys 116 or 117 can be operated according to whether a silencing or a reversal is desired. Whichever of these keys is actuated, it will be locked in its depressed position by the corresponding latch 130. After the need for this abnormal reversal or silencing has passed, the particular key held in its depressed position can be released by actuating the corresponding temporary key 114 or 115, according to which of the permanent keys is depressed.

Variations may be resorted to within the scope of the invention, and portions of the improvements may be used without others.

Having thus described my invention, I claim:

1. The combination with a plurality of computing heads, of a source of power for said heads, driving connections between said source of power and said computing heads, said driving connections having means for reversal or interruption at a single point, so as to concomitantly reverse or interrupt the action of all of said computing heads which may be active, and means for controlling said first-mentioned means so as to interrupt the action of all of said computing heads.

2. The combination with a plurality of computing heads, of a source of power for said heads, driving connections between said source of power and said computing heads, said driving connections including a member movable to different positions so as to reverse or interrupt the action of all of said computing heads according to its positions, and means for temporarily positioning said

member so as to interrupt the action of all of said computing heads.

3. The combination with a plurality of computing heads, of a source of power for said heads, driving connections between said source of power and said computing heads, said driving connections including a member movable to different positions so as to reverse or interrupt the action of all of said computing heads according to its positions, means for holding said member in position to cause activity of said computing heads, and means for moving said member so as to interrupt the action of all of said computing heads.

4. The combination with a plurality of computing heads, of a source of power for said heads, driving connections between said source of power and said computing heads, said driving connections including a member movable to different positions so as to reverse or interrupt the action of all of said computing heads according to its positions, means tending normally to hold said member in position to cause activity of said computing heads, and means for temporarily positioning said member against the tendency of said holding means, so as to interrupt the action of all of said computing heads.

5. The combination with a plurality of computing heads, of a source of power for said heads, driving connections between said source of power and said computing heads, said driving connections including a member movable to different positions so as to reverse or interrupt the action of all of said computing heads according to its positions, means normally tending to hold said member in position to cause activity of said computing heads, means for temporarily positioning said member against the action of said holding means, so as to interrupt the action of all of said computing heads, and means for holding said member so positioned to interrupt the action of all of said computing heads.

6. The combination with a plurality of computing heads, of a source of power for said computing heads, driving connections between said source of power and said computing heads whereby certain parts of said heads may be driven from said source of power, said driving connections having means for interruption so as to concomitantly interrupt the action of said computing heads which may be active, means for temporarily interrupting said driving connections so as to interrupt the action of all of said computing heads, means for detaining said driving connections in interrupted position, another means for interrupting said driving connections so as to interrupt the action of all of said computing heads, and means whereby the said first-mentioned

interrupting means may release said detaining means.

7. The combination with a plurality of computing heads, of a source of power for said heads, driving connections between said source of power and said computing heads, said driving connections including a member movable to different positions so as to reverse or interrupt the action of all of said computing heads according to its positions, means normally tending to hold said member in position to cause activity of said computing heads, means for temporarily positioning said member against the tendency of said holding means, so as to interrupt the action of all of said computing heads, and means for moving and detaining said member against the tendency of said holding means in position to interrupt the action of all of said computing heads.

8. The combination with a plurality of computing heads, of a source of power for said heads, driving connections between said source of power and said computing heads, said driving connections including a member movable to different positions so as to reverse or interrupt the action of all of said computing heads according to its positions, means for positioning said member so as to interrupt the action of all of said computing heads, a second means for positioning said member so as to interrupt the action of all of said computing heads, and means brought into action on movement of said second-mentioned means, to hold said member as positioned by either of said first- or second-mentioned means.

9. The combination with a plurality of computing heads, of a source of power, driving connections between said source of power and said computing heads whereby certain parts of all of said computing heads may be driven from said source of power, said driving connections having means for interruption so as to concomitantly interrupt the action of all of said computing heads which may be active, a key for interrupting the driving connections so as to silence all of said computing heads, a spring normally tending to hold said connections active, and locking means for holding said connections in interrupting position against the tension of said spring.

10. The combination with a plurality of computing heads, of a source of power, driving connections between said source of power and said computing heads whereby certain parts of all of said computing heads may be driven from said source of power, said driving connections having means for interruption so as to concomitantly interrupt the action of all of said computing heads which may be active, a key for interrupting the driving connections so as to silence all of said computing heads, a spring normally

tending to hold said connections active, locking means for holding said connections in interrupting position against the tension of said spring, and means for releasing said locking means, said locking means also controlling said connections.

11. The combination with a plurality of computing heads, of a source of power for said heads, driving connections between said source of power and said computing heads, said driving connections including a member movable to different positions so as to reverse or interrupt the action of all of said computing heads according to its positions, and means for moving and detaining said member in position to interrupt the action of all of said computing heads.

12. The combination with a plurality of computing heads, of a source of power for said heads, driving connections between said source of power and said computing heads, said driving connections including a member movable to different positions so as to reverse or interrupt the action of all of said computing heads according to its positions, means normally tending to hold said member in position to cause activity of said computing heads, means for temporarily positioning said member against the action of said holding means so as to interrupt the action of all of said computing heads, means to hold said member in a position to interrupt the action of all of said computing heads, and means brought into action by said temporary-positioning means to render said last-mentioned holding means ineffective.

13. The combination with a plurality of computing heads, of a source of power, driving connections between said source of power and said computing heads whereby certain parts of all of said computing heads may be driven from said source of power, said driving connections having means for reversal and interruption so as to concomitantly reverse or interrupt the action of all of said computing heads which may be active, means for manipulating said connections to vary the action thereof, and locking means holding said connections under the several types of action thereof brought into action through the medium of said manipulating means.

14. The combination with a plurality of computing heads, of a source of power, driving connections between said source of power and said computing heads whereby certain parts of all of said computing heads may be driven from said source of power, said driving connections having means for reversal and interruption so as to concomitantly reverse or interrupt the action of all of said computing heads which may be active, means for normally holding said connections with the parts thereof in a certain relation, means for manipulating said connections to vary the action thereof, and locking means held-

ing said connections against said first-mentioned holding means under the several types of action of said connections, said locking means being brought into action through the 5 medium of said manipulating means.

15. The combination with a plurality of computing heads, of a source of power, driving connections between said source of power and said computing heads whereby certain 10 parts of all of said computing heads may be driven from said source of power, said driving connections having means for interruption so as to concomitantly interrupt the action of all of said computing heads which 15 may be active, a spring normally tending to render effective said driving connections between said source of power and said computing heads, and a key for rendering said connections ineffective.

20. 16. The combination with a plurality of computing heads, of a source of power for said heads, driving connections between said source of power and said computing heads, said driving connections including a member 25 movable to different positions, so as to reverse or interrupt the action of all of said computing heads according to its positions, means to hold said member in position to cause one state of activity of said computing 30 heads, and means to move and hold said member in position to interrupt the action of all of said computing heads, one of said means being a locking means.

17. The combination with a plurality of 35 computing heads, of a source of power for said heads, driving connection between said source of power and said computing heads, said driving connections including a member movable to different positions, so as to 40 reverse or interrupt the action of all of said computing heads according to its positions, means to hold said member in position to cause activity of said computing heads, and means to move and hold said member in a 45 position to interrupt the action of all of said computing heads, one of said means being a yielding means and the other of said means being a locking means.

18. The combination with a computing 50 head, of a key for rendering said computing head temporarily inactive, a key for temporarily reversing the action of said computing head, a third key for rendering said computing head inactive, and another 55 key for reversing the action of said computing head.

19. The combination with a computing head, of a key for rendering said computing head temporarily inactive, a key for temporarily reversing the action of said computing head, a third key for rendering said computing head inactive, another key for reversing the action of said computing head, and automatic locking means for catching 60 and holding said two last-mentioned keys in

their actuated positions to make the state of the computing head which they control semi-permanent.

20. The combination with a computing head, of a key for rendering said computing head temporarily inactive, a key for temporarily reversing the action of said computing head, a third key for rendering said computing head inactive, another key for reversing the action of said computing head, 70 automatic locking means for catching and holding said two last mentioned keys in their actuated positions to make the state of the computing head which they control semi-permanent, and means actuated by said 75 two first mentioned keys for releasing said locking means.

21. The combination with a computing head, of a silencing key, means controlled thereby for temporarily rendering said computing head inactive, a silencing key for permanently rendering said computing head inactive, automatic locking means for catching and holding said last-mentioned 80 key, and means operated by said first-mentioned key for releasing said locking means.

22. The combination with a computing head, of a reversing key, means controlled thereby for temporarily reversing said computing head, a reversing key, means controlled thereby for permanently reversing the action of said computing head, locking means for said last-mentioned key, and means operated by said first-mentioned key for releasing said locking means.

23. The combination with a plurality of computing heads, of individual state controlling mechanism for said heads, a common state controlling mechanism capable of governing all of said computing heads 105 simultaneously, a temporary shift key for said common controlling mechanism, and a permanent shift key for said common controlling mechanism.

24. The combination with a plurality of computing heads, of a source of power for said heads, connections between said source of power and said computing heads, means for varying said connections to control the activity and direction of movement of each 110 of said computing heads individually, and means acting at a single point in said connections for varying the same so as to control the activity and direction of movement of all of said computing heads collectively. 115

25. The combination with a plurality of computing heads, of a source of power for said heads, driving connections between said source of power and said computing heads, said driving connections including a member 120 movable to different positions so as to reverse or interrupt the action of all of said computing heads according to its positions, means normally tending to hold said member in position to cause activity of said 125

computing heads, means for temporarily positioning said member against the tendency of said holding means to reverse the action of all of said computing heads which are 5 active, and means for detaining said member so positioned to reverse the action of said active computing heads.

26. The combination with a plurality of computing heads, of a source of power for 10 said computing heads, driving connections between said source of power and said computing heads whereby certain parts of said computing heads may be driven from said source of power, said driving connections 15 having means for reversal so as to concomitantly reverse the action of said computing heads which are active, means for detaining said driving connections in reversed position, a second means for reversing said 20 driving connections, and means whereby said first-mentioned reversing means may release said detaining means.

27. The combination with a plurality of computing heads, each having a tens carrying 25 mechanism, of gearing for driving said mechanisms including individual rotation controlling mechanisms for each of said tens carrying mechanisms, a source of power, gearing connecting said source of 30 power with said first-mentioned gearing, including shiftable clutching mechanism, a key for manipulating said shiftable clutching mechanism to one position, and a key for manipulating said clutching mechanism 35 to another position.

28. The combination with a plurality of computing heads each having a master wheel and tens carrying mechanism, of gearing for driving said master wheels, gearing 40 for driving said tens carrying mechanisms, each of said gearings including means for controlling the drive of said wheels and said tens carrying mechanisms, gearing for driving said first and second-mentioned gearings, including a reversing and drive interrupting mechanism, and a plurality of keys for varying the effective action of said last- 45 mentioned gearing.

29. The combination with a plurality of 50 computing heads, each having a master wheel and a tens carrying mechanism, of gearing for driving said master wheels including an individual means for controlling the rotation of each of said wheels, gearing 55 for driving said tens carrying mechanisms including individual means for controlling the rotation of each of said tens carrying mechanisms, a source of power, gearing connecting said first and second mentioned 60 gearings with said source of power, including silencing mechanism, and a key for controlling said silencing mechanism.

30. The combination with a plurality of computing heads, of gearing for driving all

of said computing heads, numeral keys for 65 controlling the extent of drive of said computing heads, reversing mechanism for determining the direction of drive of said gearing and said computing heads, and a plurality of keys for actuating said mechanism. 70

31. The combination with a plurality of computing heads, of gearing for driving all 75 of said computing heads, numeral keys for controlling the extent of drive of said computing heads, reversing mechanism for determining the direction of drive of said gearing and said computing heads, and a plurality of keys for actuating said mechanism to different extents. 80

32. The combination with a plurality of computing heads, each having a master wheel, of gearing for driving said master wheels, including mechanism for governing the rotation and direction of rotation of said 85 master wheels, means manipulable at a single point for governing the rotation and direction of rotation of said gearing, and a plurality of keys for actuating said means.

33. The combination with a plurality of 90 computing heads, each having a master wheel, of gearing for rotating said master wheels, including an individual changeable drive for each of said master wheels, means manipulable at a single point for governing the rotation and direction of rotation 95 of said gearing, and a plurality of keys for manipulating said means.

34. The combination with a computing head having a master wheel and tens carrying mechanism, of a reversible gearing for driving said master wheel, reversible gearing for driving said tens carrying mechanism, gearing for driving said first and second mentioned gearings, including a pair of 100 clutches shiftable to control the rotation of said first and second mentioned gearings, and a plurality of keys, any one of which may shift both said clutches simultaneously. 105

35. The combination with a computing head having a master wheel and tens carrying mechanism, of a reversible gearing for driving said master wheel, reversible gearing for driving said tens carrying mechanism, gearing for driving said first and second mentioned gearings, including a pair of clutches shiftable to control the rotation of said first and second mentioned gearings, and a plurality of keys, any one of which may shift both said clutches simultaneously, 110 115 some of said keys shifting said clutches to different points than others of said keys.

36. The combination with a plurality of computing heads, each capable of being in one of a plurality of states of adding, subtracting or remaining neutral or inactive, of a plurality of numeral keys, gearing controlled by said numeral keys so connected 125

- to said computing heads that the several heads can be in the same or different states at the same time, means for changing concomitantly the state of all of such heads as 5 may be adding and subtracting at any particular instant, a temporary reversing key for operating said means, and a permanent reversing key for operating said means.
37. The combination with a plurality of 10 computing heads, each capable of being in one of a plurality of states of adding, subtracting or remaining neutral or inactive, of a plurality of numeral keys, gearing controlled by said numeral keys so connected 15 to said computing heads that the several heads can be in the same or different states at the same time, means for changing concomitantly the state of all of such heads as may be adding and subtracting at any particular instant, a temporary silencing key 20 for operating said means, and a permanent silencing key for operating said means.
38. The combination with a plurality of computing heads, each capable of being in 25 one of a plurality of states of adding, subtracting or remaining neutral or inactive, of a plurality of numeral keys, gearing controlled by said numeral keys so connected to said computing heads that the several 30 heads can be in the same or different states at the same time, means for changing concomitantly the state of all of such heads as may be adding and subtracting at any particular instant, temporary reversing and 35 silencing keys for operating said means, and permanent reversing and silencing keys for operating said means.
39. The combination with a plurality of computing heads, of reversing mechanism 40 for each of said computing heads, reversing mechanism for all of said computing heads, and a plurality of keys for controlling said last-mentioned reversing mechanism.
40. The combination with a plurality of 45 computing heads, of a silencing mechanism for each of said computing heads, a silencing mechanism for all of said computing heads, and a plurality of keys for controlling said last-mentioned mechanism.
50. 41. The combination with a plurality of computing heads, of manually-operable means individual to each computing head for controlling the activity and direction 55 of movement of each head, and a plurality of manually-operable means common to all of said heads for also controlling the activity and direction of movement of all of said computing heads collectively, said individual manually-operable means being manipulable at any time independently of said second-mentioned manual means.
42. The combination with a computing head, of controlling mechanism for governing 60 the state of said computing head, in- cluding a shifter, a rock shaft operatively connected so as to manipulate said shifter, an arm on said rock shaft, a pin on said arm, and a plurality of key levers having cam edges engaging said pin to manipulate said rock shaft. 70
43. The combination with a computing head, of controlling mechanism for governing the state of said computing head, including a shifter, a rock shaft operatively connected so as to manipulate said shifter, an arm on said rock shaft, a pin on said arm, and a plurality of key levers having cam edges engaging said pin to manipulate said rock shaft; certain of said cam edges being of greater length than certain others 80 of said cam edges, so as to rotate said rock shaft a greater amount. 75
44. The combination with a computing head, of controlling mechanism for governing the state of said computing head, including a shifter, a rock shaft operatively connected so as to manipulate said shifter, an arm on said rock shaft, a pin on said arm, and a plurality of key levers having cam edges engaging said pin to manipulate 85 said rock shaft; certain of said cam edges being of greater length than certain others of said cam edges, so as to rotate said rock shaft a greater amount, said key levers also having slots located at the termination of 90 said cam edges and acting to lock said rock shaft against movement. 95
45. The combination with a computing head, of controlling mechanism for governing the state of said computing head, including a shifter, a rock shaft operatively connected to adjust said shifter, a pair of arms on said rock shaft, a pin on each of said arms, and key levers having cam edges 100 engaging said pins. 105
46. The combination with a computing head, of controlling mechanism for governing the state of said computing head, including a shifter, a rock shaft operatively connected to adjust said shifter, a pair of arms on said rock shaft, a pin on each of said arms, and key levers having cam edges 110 engaging said pins; each of said key levers also having a slot located at the end of said cam edges and acting to engage said pins to 115 lock said rock shaft against movement. 115
47. The combination with a computing head, of controlling mechanism for governing the state of said computing head, means for manipulating said controlling mechanism, a plurality of key levers for operating said means, a pin on one of said key levers, a rock shaft, a latch secured to said rock shaft for engaging said pin to lock one of said key levers against movement, an arm 120 on said rock shaft, and a pin on the other of said key levers adapted to engage said arm to rock said shaft and thereby disen-

gage said latch from said first-mentioned pin.

48. The combination with a computing head, of controlling mechanism for governing the state of said computing head, means for actuating said controlling mechanism, a plurality of keys for operating said means, a pair of latches for locking a pair of said keys in depressed position, a rock shaft secured to said latches, and a pair of arms secured to said rock shaft and operable by the others of said keys to release said latches.

49. The combination with a plurality of computing heads, of a source of power, driving connections between said source of power and said computing heads whereby certain parts of all of said computing heads may be driven from said source of power, said driving connections having means for reversal and interruption, so as to concomitantly reverse or interrupt the action of all of said computing heads which may be acting, and a key for controlling said driving connections for reversal or interruption.

50. The combination with a computing mechanism, of a series of numeral keys, means rendered effective thereby for controlling said computing mechanism, a series of depressible keys other than said numeral keys for temporarily and permanently selectively controlling the state of said computing mechanism, and means controlled thereby.

51. The combination with a computing mechanism capable of existing under a plurality of states as to adding, subtracting and remaining neutral, of a pair of keys, means controlled thereby for determining the same state of said computing mechanism, one of said keys enabling a temporary existence of said computing mechanism in a particular state, and locking means acting automatically to catch and hold the other of said keys in its actuated position, to maintain said computing mechanism semi-permanently in a particular state.

52. The combination with a plurality of computing heads, of an individual controlling mechanism for each of said heads for governing the state thereof, a series of depressible keys common to all of said heads, and means controlled thereby for temporarily and permanently selectively governing concomitantly the state of all of said heads.

53. The combination with a plurality of computing heads capable of existing individually in various states, of two keys for controlling the state of all of said computing heads collectively, one of said keys acting to neutralize the state and the other of said keys acting to reverse the state of all active computing heads, two other keys for also controlling the state of all of said computing

heads collectively and in accordance with 65 said first-mentioned keys, and means acting through the medium of said second-mentioned keys for preserving the respective states as determined by either of said first-mentioned or said second-mentioned keys. 70

54. In a computing machine, the combination with a plurality of computing heads, of a shaft, controlling means on said shaft for each of said computing heads to determine the state thereof, means for imparting movement to said shaft, and means for silencing said shaft and thereby all of said computing heads.

55. In a computing machine, the combination with a plurality of computing heads, of 80 a shaft, means for imparting differential movements to said shaft, means on said shaft connecting said shaft and each of said computing heads for determining the state of said heads as to addition or subtraction, and 85 means for silencing said shaft and thereby all of said computing heads.

56. In a combined typewriting and computing machine, the combination with reversing and disconnecting means, of depressible keys for temporarily and permanently controlling said reversing and disconnecting, and a single shaft for all said keys whereby they are effective.

57. In a computing machine, the combination of a plurality of computing heads, a source of power, a shaft between said source of power and said computing heads, controlling means on said shaft for each of said computing heads to determine the state 100 thereof as to addition or subtraction, and means for interrupting the connection between said source of power and said shaft to thereby silence all of said computing heads.

58. The combination with a plurality of computing heads, of a source of power for said heads, driving connections between said source of power and said computing heads, said driving connections including a member movable to different positions so as to reverse or interrupt the action of all of said computing heads according to its positions, means normally tending to hold said member in position to cause activity of said computing heads, means for temporarily positioning said member against the tendency of said holding means so as to reverse the action of said computing heads which are active, means for detaining said member in 110 said reverse position, and means brought into action by said temporary - positioning means acting to render nugatory said detaining means.

59. The combination with a plurality of computing heads, of a source of power for said heads, driving connections between said source of power and said computing heads,

said driving connections including a member movable to different positions, so as to reverse or interrupt the action of all of said computing heads according to its positions, 5 means normally tending to hold said member in position to cause activity of said computing heads, means to temporarily position said member against the tendency of said holding means to interrupt the action of all 10 of said computing heads, means to temporarily position said member against the tendency of said holding means to reverse the action of said computing heads which are active, means acting against the tendency of said holding means to move and hold said member in position to interrupt the action of all of said computing heads, and means acting against the tendency of all said holding means to move and hold 15 said member in position to reverse the action of said computing heads which are active, said temporarily-interrupting means and said temporarily-reversing means controlling respectively said interrupting-holding means and said reversing-holding means.

60. The combination with a computing head having a master wheel and tens-carrying mechanism, of a reversible gear for driving said master wheel, reversible gearing 30 for driving said tens-carrying mechanism, gearing for driving said first and second mentioned gearings including a pair of clutches shiftable to control the rotation of said first and second mentioned gearings, a 35 key adapted to shift said clutches to one point, and a key adapted to shift said clutches to another point.

61. In a computing machine, the combination with two computing heads and means 40 manually settable to separately determine how said heads shall be effective, of a single shaft for controlling both said heads simultaneously, and a plurality of keys effective on said shaft.

45. 62. The combination with a plurality of computing heads, of a source of power for said heads, driving connections between said source of power and said computing heads, said driving connections including a member movable to different positions, so as to reverse or interrupt the action of all of said computing heads according to its positions, means to yieldingly hold said member in 50 position to cause activity of said computing heads, means to move and lock said member against the action of said yielding means in position to interrupt the action of all of said computing heads, and means to temporarily position said member against the action of all 55 of said yielding means to interrupt the action of all active computing heads, said last-mentioned positioning means taking control of said member and holding it in the position to which it has been moved when 60

under the influence of said locking means 65 and acting to render said locking means ineffective.

63. The combination with a plurality of computing heads, of a source of power for said heads, driving connections between said source of power and said computing heads, said driving connections including a member movable to different positions, so as to reverse or interrupt the action of all of said computing heads according to its positions, 70 means to hold said member in position to cause activity of said computing heads, and means to move and hold said member in position to reverse the state of activity of said computing heads which are active, one of 75 said means being a locking means.

64. The combination with a plurality of computing heads, of a source of power for said heads, driving connections between said source of power and said computing heads, 80 said driving connections including a member movable to different positions, so as to reverse or interrupt the action of all of said computing heads according to its positions, means to hold said member in position to 85 cause activity of said computing heads, and means to move and hold said member in a position to reverse the action of all of said computing heads which are active, one of 90 said means being a yielding means and the 95 other of said means being a locking means.

65. The combination with a plurality of computing heads, of a source of power for said heads, driving connections between said source of power and said computing heads, 100 said driving connections including a member movable to different positions, so as to reverse or interrupt the action of all of said computing heads according to its positions, means to yieldingly hold said member in 105 position to cause activity of said computing heads, means to move and lock said member against the action of said yielding means in a position to reverse the action of all of said computing heads which are active, and means to temporarily position said member against the action of said yielding means to 110 reverse the action of all said computing heads which are active, said last-mentioned positioning means taking control of said member and holding it in the position to which it has been moved when under the influence of said locking means and acting to render said locking means ineffective. 115

66. The combination with a plurality of computing heads, of a source of power for said heads, driving connections between said source of power and said computing heads, said driving connections including a member movable to different positions so as to reverse or interrupt the action of all of said computing heads according to its positions, 120 means for moving and holding said member

in a position so as to interrupt the action of all of said computing heads, and means for moving and holding said member in a position to reverse the action of all of said computing heads that are active.

67. In a combined typewriting and computing machine, the combination with a mechanism adapted to subtract and to print, of a key effective to cause said mechanism to add, a latch adapted to hold said key effective when depressed, and a second key similarly effective and adapted to release said first-named key when operated.

68. In a computing machine, the combination with numeral keys and state-controlling keys effective to control the state of the computing connections, of separate latches for said state-controlling keys, and a single shaft universal to said latches to release them.

69. The combination with a plurality of computing heads, of a source of power for said heads, driving connections between said source of power and said computing heads, said driving connections including a member movable to different positions so as to reverse or interrupt the action of all of said computing heads according to its positions; means for positioning said member so as to reverse the action of all of said computing heads, a second means for positioning said member so as to reverse the action of all of said computing heads, and means brought into action on movement of said second-mentioned means, to hold said member as positioned by either of said first- or second-mentioned means.

70. The combination with a plurality of computing heads, capable of existing individually in various states, of means for controlling the state of all of said computing heads collectively, a second means for controlling the state of all of said computing heads collectively, and means brought into action through the medium of said second-mentioned means, for preserving the states as determined by either of said first- or second-mentioned means.

71. The combination with a plurality of computing heads, of a source of power for said heads, driving connections between said source of power and said computing heads, said driving connections including a member movable to different positions so as to reverse or interrupt the action of all of said computing heads according to its positions; means normally tending to hold said member in position to produce one state of said computing heads, means for positioning said member against the tendency of said holding means to vary the state of said computing heads as determined by said first-mentioned means, another means for also positioning said member against the tendency of said

holding means to vary the state of said computing heads as determined by said first-mentioned means, a detaining means brought into action through the medium of said last-mentioned means to detain said member as positioned by either of said first or second-mentioned positioning means, and means brought into action through the medium of said second-mentioned positioning means to render ineffective said detaining means to thereby restore said member to the action of said holding means.

72. The combination with a plurality of computing heads, of a source of power for said heads, driving connections between said source of power and said computing heads, said driving connections including a member movable to different positions so as to reverse or interrupt the action of all of said computing heads according to its positions; means normally tending to hold said member in position to cause activity of said computing heads, means for temporarily positioning said member against the tendency of said holding means to reverse the action of all of said computing heads which are active, and means for moving and detaining said member in position to reverse the action of said computing heads.

73. The combination with a plurality of computing heads, of a source of power for said heads, driving connections between said source of power and said computing heads, said driving connections including a member movable to different positions so as to reverse or interrupt the action of all of said computing heads according to its positions; means for moving said member to a position so as to interrupt the action of all of said computing heads, and means for moving said member to a position to reverse the action of all of said computing heads which are active.

74. The combination with a plurality of computing heads, of a source of power for said heads, driving connections between said source of power and said computing heads, said driving connections including a member movable to different positions so as to reverse or interrupt the action of all of said computing heads according to its positions; means normally tending to hold said member in position to cause activity of said computing heads, means for temporarily positioning said member against the tendency of said holding means so as to interrupt the action of all of said computing heads, and means for moving and holding said member in position to reverse the action of all of said computing heads which are active.

75. The combination with a plurality of computing heads, of a source of power for said heads, driving connections between said

- source of power and said computing heads, said driving connections including a member movable to different positions, so as to reverse or interrupt the action of all of said computing heads according to its positions, means normally tending to hold said member in position to cause activity of said computing heads, means to move and hold said member against the tendency of said holding means to interrupt the action of all said computing heads, and means to move and hold said member against the tendency of said holding means to reverse the action of all of said computing heads which are active.
- 15 76. The combination with a plurality of computing heads, of a source of power for said heads, driving connections between said source of power and said computing heads, said driving connections including a member movable to different positions, so as to reverse or interrupt the action of all of said computing heads according to its positions, means normally tending to hold said member in position to cause activity of said computing heads, means for temporarily positioning said member against the tendency of said holding means to interrupt the action of all of said computing heads, means to temporarily position said member so as to reverse the action of said driving connections on all of said computing heads, and means to hold said member in interrupting position.
- 30 77. The combination with a plurality of computing heads, of a source of power for said heads, driving connections between said source of power and said computing heads, said driving connections including a member movable to different positions, so as to reverse or interrupt the action of all of said computing heads according to its positions, means normally tending to hold said member in position to cause activity of said computing heads, means for temporarily positioning said member against the tendency of said holding means to interrupt the action of all of said computing heads, means to temporarily position said member against the tendency of said holding means to reverse the action of all of said computing heads which are active, and means to hold said member in reversing position.
- 45 78. The combination with a plurality of computing heads, of a source of power for said heads, driving connections between said source of power and said computing heads, said driving connections including a member movable to different positions, so as to reverse or interrupt the action of all of said computing heads according to its positions, means to temporarily position said member against the tendency of said holding means to reverse the action of all of said computing heads which are active, and means to move and hold said member in interrupting position.
- 55 79. The combination with a plurality of computing heads, of a source of power for said heads, driving connections between said source of power and said computing heads, said driving connections including a member movable to different positions, so as to reverse or interrupt the action of all of said computing heads according to its positions, means normally tending to hold said member in position to cause activity of said computing heads; means to position said member against the tendency of said holding means to interrupt the action of all of said computing heads, means to temporarily position said member against the tendency of said holding means to reverse the action of all of said computing heads which are active, and means to move and hold said member in reversing position.
- 80 80. The combination with a plurality of computing heads, of a source of power for said heads, driving connections between said source of power and said computing heads, said driving connections including a member movable to different positions, so as to reverse or interrupt the action of all of said computing heads according to its positions, means normally tending to hold said member in position to cause activity of said computing heads, means for temporarily positioning said member against the tendency of said holding means to interrupt the action of all of said computing heads, means for temporarily positioning said member against the tendency of said holding means to reverse the action of said computing heads which are active, means acting against the tendency of said holding means to move and detain said member in position to interrupt the action of all of said computing heads, and means also acting against the tendency of said holding means to move and detain said member in position to reverse the action of said computing heads which are active.
